VALVE FOR INTERNAL-COMBUSTION ENGINES

Frank Fix, Detroit, Mich.

Application April 9, 1943, Serial No. 482,466

9 Claims.

(Cl. 123—78)

This invention relates to valves for internal combustion engines of a character to be utilized with either the intake or exhaust ports of the engine.

The object of the invention is to provide a new and improved valve structure of such character of construction as to avoid corrosion or burning of the sealing face of the valve due to the flow of either the combustible mixture or the hot exhaust gases and to prevent an accumulation of carbon or other foreign matter between the valve and the surface with which it cooperates in opening or closing the engine port.

In the poppet type of valve ordinarily in use in internal combustion engines, the valve has a tapered face and a tapered seat and the stem of the exhaust valve is subject to influence of the heat of the exhaust gases discharging to an exhaust conduit controlled by the valve and the intake valve is also subject to the heat of the burning gases within the cylinder.

My improved valve structure as hereinafter described avoids warping of the valve or the corrosion of the valve seat and provides a valve of such character of construction and arrangement of parts as to avoid the usual troubles arising in use of valves of the poppet type as the contacting surface of the parts of my improved valve are at all times maintained clean and further provide a more effectual sealing of the engine port.

These and other objects and features of the invention are hereinafter more fully described and claimed and a valve structure embodying my invention is shown in the accompanying drawings in which—

Fig. 1 is a plan view showing a portion of the head of an internal combustion engine and one type of valve operating mechanism.

Fig. 2 is a vertical section taken on line 2—2 of Fig. 1, showing the engine head including my improved valve structure associated with a push rod type of valve operating mechanism.

Fig. 3 is an elevation partly in section looking at the right hand side of Fig. 1 and showing the valve operating mechanism.

Fig. 4 is a vertical section taken through a pair of engine cylinders and showing my improved valve structure as operated by an overhead cam shaft.

Fig. 5 is a plan view thereof.

Fig. 6 is an enlarged cross section of my improved valve structure and the cams for operating the same.

Fig. 7 is a series of three diagrams showing the positions of the valve parts through one cycle of operation.

An internal combustion engine valve involving my improved features of construction avoids many of the troubles arising in the usual poppet type of valve which, as aforesaid, is subject to

corrosion and warpage due to the excessive heat to which the valve may be subjected in operation of the engine in that the meeting surfaces between the intake valve and the member with which it is in contact and relative to which it is movable is at all times shielded from contact with the inflowing combustible gases and the cooperating surfaces of the exhaust valve are free from contact by the exhaust gases discharging from the cylinder on the exhaust stroke of the piston as will be more readily understood from Fig. 4 in which there is shown a pair of cylinders 1 and 2 shown side by side with the piston 3 of the cylinder 1 on the intake stroke and the piston 4 of the cylinder 2 on the compression stroke. The detachable head 5 shown provides an intake manifold having the passageway 6 and the head is apertured to receive a reciprocal tubular element 7 terminating at its lower end with the upper edge of the passageway 6. The said edge 6 is spaced from the lower apertured face 8 of the manifold and said aperture has a ring member 9 of an L form in cross section and in effect provides a continuation of the tubular element 7 except for the space between the lower end of the tubular element 7 and the upper end of the ring member 9.

The tubular element or sleeve 7 is open ended and reciprocably mounted in the vertical aperture 7a provided therefor in the head 5. The outer end of the sleeve 7 is flanged at its upper end and the under side of the flange is engaged by the coiled spring 10 seating in a recess provided in the engine head as shown. The spring 10 tends to move the sleeve 7 outwardly of the head 35 and the upper end of the sleeve 7 is inwardly tapered. A head 11 is mounted on a stem 12 and a valve 13 is fixed to the lower end of the stem. The stem 12 is reciprocable in an aperture provided in a transverse wall 14 having apertures 15 therein as shown while the head 11 has apertures 16 so that reciprocation of the valve and head in the sleeve 7 is not restricted by air pressure. The valve 13 is the intake valve of the cylinder 1 and the valve 13a an exhaust valve of the cylinder 2 and the two valves are alike in structure and mechanical operation.

By means of the coiled spring 10 seating at its lower end on the wall 14 and the upper end 50 of the spring seating on the washer 18 on the stem 12, the valve 13 is raised to the position shown in Fig. 4 with the lower end of the valve periphery flush with the lower end of the sleeve 7 and the manifold passageway 6 providing for flow of gas from the intake manifold through the ring element 9 and thence to the engine cylinder 1 on the intake stroke of the piston 3 therein.

For operation of the valve 13 to close or open the port provided by the ring 9, I provide an overhead cam shaft 19 having a central cam 20 and

cams 21 and 22 on opposite sides of the cam 20 and in spaced relation therewith.

The cam 20 engages the head 11 on the stem 12 of the valve 13 and serves to reciprocate the valve while the cams 21 and 22 serve to reciprocate the sleeve 7. The cam shaft 19 is rotated in timed relation with the engine crank shaft by the commonly known mechanism (not here shown).

The relationship of the cams on the cam shaft 19 is shown more clearly in Fig. 6 in which it will be seen that the upper end of the sleeve about its central opening is tapered as indicated at 23 to permit the cam 20 to turn into the open end of the sleeve and depress the head 11 while the sleeve 7 is depressed by the cams 21 and 22. The cams are of such form that the sleeve 7 is moved to contact at its lower end with the ring 8 and the piston 13 is secondarily moved to the position shown at 13a at the right hand side of Fig. 4 and with the sealing ring 13b of the valve covering the interstice between the lower end of the sleeve 7 and the upper edge of the ring 8a and thus sealing the intake passageway to the cylinder during the compression and the exhaust stroke of the piston. On completion of the exhaust stroke of the piston, the valve 13 or 13a is permitted by its cam to move upwardly until the lower peripheral edge of the valve aligns with the lower end of the sleeve and the cams by their continual rotation and relationship thus permit both the sleeve and the valve to move as a unit to the position shown at the left side of Fig. 4 and open the intake manifold to the cylinder.

This latter position of the valve is attained just prior to the intake stroke of the respective piston and the valve is retained in such position by reason of the shape of the cams. The successive positions of the valve 13 and sleeve 7 are shown in the diagrammatic views grouped as Fig. 7.

The foregoing description is practically confined to the valve operating structure shown in Figs. 4, 5 and 6. In Figs. 1, 2 and 3 I have shown the same valve structure and sleeve while the operating mechanism is of the push rod type which includes a cam shaft 30 to be understood as being operated by the engine shaft (not shown) and on this shaft are cams 31 and 32 corresponding to the cams 20 and 22 shown in Fig. 6, the cam 31 being similar to the cam 20 in Fig. 6 and the cam 32 being similar to the cam 22 of Fig. 6. The cam 31 directly engages the push rod 33 while the cam 32 engages the lower end of a sleeve 34 in which the push rod is encased. The upper end of the push rod 33 engages a lever 35 while the sleeve has end portions 36 and 37 which respectively engage the two levers 38 and 39 connected together as by cross bars 40 and 41. The levers 38 and 39 have end portions indicated at 42 in Fig. 2 which engage the periphery of the sleeve 43 while the terminal end of the lever 35 engages the head of the valve structure 44.

The functional relationship of the valve in respect to the piston and the operation of the valve parts to open and close the manifold passageway to the cylinder are the same as and function similarly to the corresponding parts as shown in Figs. 4 and 6 and thus are believed not to require further description except that it is to be noted that the lower end of the valve operating rod and cam shaft are out of position in respect to the motor or engine shaft not here shown. The sleeve is slidable in brackets 45 and 46. It

is thus not material to this invention whether one or the other forms of a valve and sleeve actuating mechanism may be used.

It is also to be understood that, while I have not shown the engine exhaust valve, such exhaust valve will be approximately identical with the structural arrangement of parts of the intake valve hereinbefore described in detail and that either an overhead cam shaft may be utilized for operation of the valve or the push rod type of mechanism may be utilized therefor depending upon the type of engine with which the valve is to be utilized as will be readily understood by those skilled in the art.

Irrespective of the form of valve operating mechanism utilized the principal utility of the valve structure resides in the fact that corrosion of the valve seat or the fouling of the valve seat is practically eliminated in the form and arrangement of the valve parts herein disclosed in which the valve instead of actually seating in the manner of the usual poppet valve nevertheless seals or opens the port to flow of either intake or exhaust gases by cylindrical parts in slideable contact and any dirt that would in the poppet type of valve possibly adhere to the valve face or the seat, will be eliminated in the type of valve herein disclosed as the face of the valve member slideable in the sleeve would tend to remove any extraneous material or prevent accumulation thereof on the contacting surfaces of the valve and sleeve. In the case of an exhaust valve the slideable valve, as well as the end of the sleeve in which it reciprocates, is moved outwardly in respect to the port controlled thereby and only the external face of the valve 13 of Fig. 4 or 44 of Fig. 2 would be subjected to heat and the stem of the valve is largely protected by being within the transverse wall 14 in Fig. 4 or 14a in Fig. 2 and thus shielded materially from influence of heat developed within the engine cylinder.

It is believed evident from the foregoing description that my improved valve structure as hereinbefore described and as shown in the drawings, provides an arrangement resulting in an improved structure of simple arrangement and relationship of parts well adapted for and securing an improved operation of the engine and a materially longer life of the valve parts under normal conditions of use and that various alterations and changes may be made without departing from the spirit and scope of the invention as set forth in the appended claims.

Having thus fully described my invention, its utility and mode of operation, what I claim and desire to secure by Letters Patent of the United States is—

1. A valve mechanism for use with internal combustion engines having a reciprocating piston and a head providing an inlet and exhaust manifold each having a port opening to the engine cylinder, a valve mechanism for use with each port, each valve mechanism comprising a sleeve reciprocable in the engine head providing the intake and exhaust passageways, a ring like member supported in the casting at the head of the engine of the same diameter and in alignment with the reciprocable sleeve and the respective intake or exhaust passageway having an outer wall spaced from the port, a sleeve member aligned with the said port and movable to engage the ring like member and to close the passageway to the port or movable in the opposite direction to opening the passageway to the port, a valve means slidable in the cylindrical tubular member

in timed relation with the movement of the sleeve to position within the ring member and sealing the interstice between the ring member and the sleeve when in contact and movable outwardly of the sleeve with the outer face of the valve aligned with the lower end of the sleeve and thereafter movable with the sleeve to open the port to the passageway.

2. A valve mechanism adapted for use with either the intake or the exhaust port provided in the cylinder head of an internal combustion engine having intake and exhaust passageways opening thereto, comprising a sleeve slidably in a way provided in the head to which the passageway opens, a ring member providing an opening between the respective passageway and the cylinder, a valve reciprocable in the sleeve to close or open the passageway to the cylinder, and means for moving the sleeve to close the passageway to the port and sequentially move the valve into the ring member to close the interstice between the sleeve and the ring during the period of development of pressure within the engine cylinder and to thereafter sequentially move the valve and then the sleeve to open the passageway to the cylinder.

3. A valve mechanism for use with the cylinder of an internal combustion engine having a head and an intake passageway including a port opening to the cylinder, comprising a sleeve slidably mounted in the head in axial alignment with the port, a ring member mounted in the port in spaced relation and in alignment with the sleeve, a valve reciprocable in the sleeve, mechanism for moving the sleeve to engagement with the ring member and to sequentially move the valve to bridge the interstice between the sleeve and the ring member, mechanism for causing movement of the sleeve and valve in timed relationship in respect to the piston movement to open the port and permit flow of gases to the cylinder on the intake movement thereof, and to close the port to the passageway during the compression and the firing of the gases.

4. A valve mechanism for use with the cylinder intake and exhaust ports of an internal combustion engine having a head, an intake passageway therein including a port opening to the cylinder, and an exhaust passageway including a port opening to the cylinder, said valve mechanism comprising a sleeve slidably mounted in the head in axial alignment with the respective port, a ring member mounted in the port in alignment with the respective sleeve, a cylindrical valve reciprocable in the sleeve, and mechanism for moving the sleeve and valve to open and close the respective ports in timed relation to permit the introduction of gases in the cylinder and the sequential compression of the introduced gases, firing, and exhausting of the burned gases.

5. A valve mechanism for an internal combustion engine having a head including a passageway for gases and an opening between the passageway and the cylinder, comprising a sleeve reciprocable in the head, a ring member in the said opening in alignment with the sleeve, spring means tending to move the sleeve outwardly to open the passageway and a spring means tending to move the valve outwardly in the sleeve, and mechanism for sequentially moving the sleeve and the valve to effect closing or the opening of the port to the cylinder in timed relation to the piston movement.

6. A valve mechanism for controlling the in-

take port of an internal combustion engine including an intake manifold having a cylindrical opening between a wall thereof and the cylinder and an axially aligned cylindrical opening in the opposite wall, comprising a sleeve reciprocable in the last named cylindrical opening, spring means tending to move the sleeve outwardly in respect to its opening, a valve of cylindrical form reciprocable in the sleeve, spring means tending to move the valve outwardly of the sleeve, and cam means operable to cause movement of the sleeve and the valve in sequential relation to close the port during the period of development of pressure in the cylinder and to open the port to the manifold on the intake movement of the piston.

7. Valve mechanism for controlling a port of an internal combustion engine having a manifold having a cylindrical opening between a wall thereof and the cylinder and a cylindrical opening in its opposite wall in axial alignment with the first named opening, comprising a sleeve reciprocable in the last named cylindrical opening, spring means tending to move the sleeve outwardly in respect to the opening, a valve of cylindrical form reciprocable in the sleeve, a stem for the valve, spring means on the said stem tending to move the valve outwardly of the sleeve, a ring like element in the first named manifold opening to the cylinder aligned with the sleeve, means for moving the sleeve against the tension of its spring to engagement with the ring to close the manifold opening to the cylinder, and means for sequentially moving the valve inwardly of the sleeve against the tension of its spring into the ring seat for the sleeve to thereby close the opening of the manifold to the cylinder.

8. A valve mechanism for controlling the exhaust port of an internal combustion engine including a manifold having a cylindrical opening between a wall thereof and the cylinder and an axially aligned cylindrical opening in the opposite wall, comprising a sleeve reciprocable in the last named cylindrical opening, spring means tending to move the sleeve outwardly in respect to the last named cylindrical opening, a valve of cylindrical form reciprocable in the sleeve in sealed relation therewith, spring means tending to move the valve outwardly of the sleeve, and cam means operable to cause movement of the sleeve and the valve in sequential relation in respect to the opening to seal the port from the manifold during the period of development of pressure in the cylinder and to open the port to the manifold during the period of the exhaust stroke of the piston.

9. A valve for use in controlling the port of an internal combustion engine having a reciprocable piston, a manifold including a port providing for flow of gases to or from the engine cylinder and said manifold having an opening to the cylinder, comprising a sleeve supported in the manifold in axial alignment with the port and movable to position to seal the port to the manifold or to position to open the same thereto, a valve reciprocable in the sleeve, means for causing the movement of the sleeve and valve to first move the sleeve to enclose the port and to then move the valve to seal the interstice between the end of the sleeve and the wall about the port during one period of piston movement and thereafter to first move the valve outwardly in respect to the port and then move the valve and sleeve in unison to open the port to the passageway.
